UNITED STATES PATENT OFFICE.

WILLIAM H. WARREN, OF NEW YORK, N. Y.

CALIPERS AND DIVIDERS.

SPECIFICATION forming part of Letters Patent No. 228,958, dated June 15, 1880.
Application filed December 27, 1879.

To all whom it may concern:

Be it known that I, WILLIAM H. WARREN, of the city, county, and State of New York, have invented a new and useful Improvement 5 in Measuring-Instruments, of which the following is a specification.

Figure 1 is a front elevation of my improvement as applied to a pair of calipers. Fig. 2 is a transverse section on line x x , Fig. 1. 10 Fig. 3 is a transverse section of elevation of a pivoted stud. Fig. 4 is a transverse sectional elevation of the shouldered revolving stud.

Similar letters of reference indicate corresponding parts.

15 This invention relates to measuring-instruments, such as calipers, compasses, dividers; and it consists of revolving studs or pivots fixed at any convenient points on the instrument, and in combination with a slotted bar, 20 whereby the legs of the instrument may be adjusted by means of screw and spring without loosening the clamping screws and nuts.

In the drawings, A A represent legs of a 25 pair of calipers designed for inside measurement, pivoted together in the ordinary manner by a pivot, a.

Pivoted on the upper end of one of the legs is a stud, B, provided with a lateral bore, b, and sockets c c in the opposite faces of the 30 stud at each end of the bore b.

Passing through the upper end of the opposite leg is a pivot, C, on which is firmly fixed a shouldered stud, D, whose shoulder fits into the slot f of the slotted bar E, so that the said 35 bar E can move back and forth on the said stud D and turn with it.

The slotted bar E is a little thicker than the shoulder of the stud D, so that when the washer F is set over the screw-pivot C and the clamp- 40 ing-nut G is screwed as tightly as may be upon it the said slotted bar E is firmly held, so that

it will not slide on the stud D when the calipers are adjusted by the nut K.

From one end of the slotted bar E there projects a screw-rod, H, encircling which is a 45 spiral spring, I, and the end of this screw-rod H passes through the bore b of the stud B, and has screwed on its end the nut K. The sockets c c in this stud B receive and hold, respectively, an end of the spiral spring and the 50 end of the nut K.

It will be seen that, at whatever angle the legs A A may be separated, the slotted bar E and the screw-rod H maintain their relative positions with the studs B and D, and that without releasing or loosening the clamping-nut G the legs of the calipers can be adjusted to any angle by means of the screw-nut K.

Although in the accompanying drawings I have shown my invention as applied to a pair 60 of calipers, it can be applied with equal advantage to other instruments or machinery.

Having thus described my invention, I claim as new and desire to secure by Letters Patent—

1. As a means of adjusting the limbs of measuring-instruments, the pivoted studs B D, slotted bar E, screw-rod H, spring I, and screw-nuts G K, in combination with the limbs A A, substantially as herein shown and described. 65

2. In a measuring-instrument, the pivoted stud B, constructed with sockets c c and bore b, substantially as herein shown, and for the purpose described. 70

3. In a measuring-instrument, the slotted bar E and screw-rod H, constructed substantially as herein shown and described. 75

WILLIAM H. WARREN.
